Primary Examiner — Garth Rademaker*Assistant Examiner* — Katelin G Kloberg(74) *Attorney, Agent, or Firm* — Sturm & Fix LLP(57) **CLAIM**

The ornamental design for a shoe strap, as shown and described.

DESCRIPTION

FIG. 1 is a perspective view of a shoe strap, showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The tightly-spaced lines shown on the front and rear of the design illustrate hook-and-loop textures on the front and rear surfaces and are not intended to indicate two-dimensional surface patterns.
